UNITED STATES PATENT OFFICE.

CHRISTIAN N. SMITH, OF ELGIN, ILLINOIS.

SAFETY PLATE-HOLDER FOR ELECTROTYPE AND STEREOTYPE SHAVING MACHINES.

1,349,736.

Specification of Letters Patent. Patented Aug. 17, 1920.

Application filed July 29, 1918. Serial No. 247,277.

To all whom it may concern:

Be it known that I, CHRISTIAN N. SMITH, a citizen of the United States, residing in Elgin, in the county of Kane and State of Illinois, have invented certain new and useful Improvements in Safety Plate-Holders for Electrotype and Stereotype Shaving Machines, of which the following is a specification.

10 This invention relates to plate-holders for electrotype and stereotype shaving machines, and particularly to plate-holder attachments which are adapted to be attached to or mounted upon machines for shaving 15 electrotype or stereotype plates, or other or similar metallic plates to be shaved or planed.

The principal object of the invention is to provide a simple, economical and efficient 20 safety plate-holder for machines for shaving or planing electrotype or stereotype plates or other or similar metallic plates, and an improved plate-shaving machine.

Other and further objects of the invention 25 will appear from an examination of the following description and claims, and from an inspection of the accompanying drawings, which are made a part hereof.

The invention consists in the features, 30 combinations, parts, and details of construction herein described and claimed.

In the accompanying drawings; Figure 1 is a view in side elevation of my improved 35 plate-holder, showing the same attached to an electrotype and stereotype shaving machine made in accordance with my invention, with parts of the shaving machine broken away;

Fig. 2 is a plan view of the plate-holder 40 attachment or device shown in Fig. 1, showing the same in position upon the type of electrotype and stereotype shaving machine shown in Fig. 1, with parts of the shaving machine broken away or omitted;

Fig. 3 is a view in side elevation of my 45 improved plate-holder attachment, with parts broken away, showing the same attached to and adapted to operate in connection with a different form of stereotype and electrotype shaving machine from that shown in Figs. 1 and 2, the machine shown in Fig. 3 being of well known form; and

Fig. 4, shows a pivoted safety-plate holder 50 of modified form, in perspective, adapted to be attached to any ordinary shaving machine.

In providing an electrotype and stereotype shaving machine with a plate-holder attachment constructed in accordance with my invention, I provide an electrotype and 60 stereotype shaving or planing machine 1 having a plate-supporting bed 2 mounted upon a suitable supporting frame comprising legs 3, longitudinal frame members 4 and transverse frame members 5, and having 65 the usual receptacle or container 6 for receiving shavings and waste material.

A movable knife-supporting head, cutter head or carriage 7 is mounted in slidable engagement with the side frame members 4 70 and in position to extend transversely across the plate-supporting bed 2, being slidably connected with the frame by means of carriage end-frame members 8 which are supported upon and in slidable engagement 75 with the side-frame members 4 of the stationary main frame, the carriage frame members 8 being provided with bottom jaws or flanges 9 which extend beneath and in sliding engagement with side frame members 4 located on opposite sides of the bed or forming the side margins of the bed. The end frame members 8 of the horizontally movable knife-supporting head or carriage are connected by means of a transverse carriage frame member 10, or other suitable 80 connecting means adapted to connect the end-frame members of the carriage in such a manner as to form a strong and suitable supporting frame, carriage or head for supporting and guiding the knife in the operation of shaving or planing stereotype or electrotype or similar metallic plates laid upon the bed in position to be operated upon.

A knife 11 is mounted in or supported 85 by the carriage or knife-supporting head in any desired ordinary and well known manner; and suitable means is provided for driving and reversing the direction of movement of the knife-supporting head or carriage. In the plate-holder and improved form of electrotype and stereotype shaving machine shown in Figs. 1 and 2 of the drawings, the knife or cutter blade 11 is adjustably supported upon a pivoted supporting 90 plate or rear clamping member 12 fixed to an axle 13, the opposite ends of which are journaled in the end-frame members 8 of the cutter-head or carriage; and a front knife-engaging clamping member or plate 14 is secured in clamping engagement with the forward upper side of the knife by

means of securing screws 15 which extend through suitable openings in the clamping plate or jaw 14 and are anchored in threaded engagement with the rear plate or clamping jaw 12. Adjusting screws 16 mounted in threaded engagement with the knife-supporting member 12 and with their inner ends in engagement with the back edge of the knife, and having lock nuts 17 thereon, are adapted to enable the knife to be adjusted and secured in the desired position between the jaws. Crank arms 18, fixed to opposite ends of the rock-shaft 13 engage corresponding ends of a roller 19 which has its opposite end portions mounted in upwardly and downwardly movable sliding blocks 20 mounted between vertical guides or ways 21 and provided with springs 22, adjusting screws 23 and adjusting nuts 24 for holding the sliding blocks 20 and roller 19 in any position in which they are adapted to be adjusted. Springs 25 connected with the crank arms 18, serve to hold said arms yieldingly in engagement with the roller 19, and to permit the same to be raised against the tension of said springs so as to raise the bottom ends of the crank arms and thereby lift the cutting edge of the knife from its lowered cutting position. The knife-supporting head or carriage is provided with rearwardly extending toothed racks 26 which are operatively connected with a main driving shaft 27 by means of a counter-shaft 28 having toothed pinions 29 fixed thereto and in toothed engagement with the racks 26, a spur gear wheel 30 being fixed to the rotative counter-shaft 28 and in toothed engagement with a spur pinion 31 fixed to the main drive shaft 27. The main drive shaft 27 is provided with one or more belt pulleys or drive wheels 32 mounted in concentric relation to the main drive shaft. I prefer to employ two drive wheels 32 in the form of belt pulley wheels each adapted to be connected with a motor or source of power so as to rotate in opposite directions when in operation. And the main drive shaft is provided with suitable clutch mechanism—not shown—which may be of any ordinary and well known or suitable form adapted to operatively connect the shaft with the drive wheel mechanism in such a manner that the shaft may be rotated in opposite directions successively, as desired, so as to cause the knife-supporting carriage to travel over the plate-supporting bed, and over any plate thereon, in opposite directions. Trip-supporting rods 33 are mounted in stationary supports 34 on opposite sides of the main frame of the machine and bed. Each of these rods is provided with a rear tripping member or detent 35 near one extremity of the bed and a forward tripping finger or detent 36 near the other or forward extremity of the bed, but both adjustably secured to the rods on which they are mounted. Slidable roller-supporting and tripping members 37 are slidably mounted on the carriage on opposite sides of the bed and in supporting engagement with the opposite ends of the roller 19, when the latter is in raised position—the roller being supported by the sliding blocks in which it is journaled, in position to be pressed down against the upper surface of a plate so as to travel over the plate in advance of the knife, but out of engagement with the crank arms 18 when said roller and the knife edge are in lowered operative position. The tripping members 37 on the carriage are in position to travel back and forth between the tripping members 35 and 36, and are slidably supported on the carriage by bolts 38 in elongated slots 39, and have raised roller-supporting cam portions 41, adapted to engage and support the roller 19 in raised position. Depending shoulders 40 on the members 37 are adapted to be engaged by the tripping fingers 35 and 36 so as to cause the raised bosses 41 to engage and raise the roller 19 and thereby raise the knife when the carriage and knife have reached their forward limit of movement and the shoulders 40 are engaged by the corresponding tripping fingers 36 at or near the forward extremity of the bed. The knife is thus permitted to return to its starting point with its edge raised above and out of engagement with the plate to be operated upon, until the depending tripping shoulders 40 come into engagement with the rear tripping fingers 35, thus operating the roller-supporting members 37 and permitting the roller 19 to be lowered into engagement with the top surface of the plate to be operated on, and out of supporting engagement with the crank or lever arms 18 fixed to the pivoted knife-supporting member 12. A pedal 43 is operatively connected with the clutch mechanism of the main drive shaft in any ordinary or suitable known manner, so as to cause the carriage to be moved forwardly when that pedal is operated; and a pedal 44 is in like manner operatively connected with the clutch mechanism so as to cause the main driving shaft to be operated in a reversed direction and cause the carriage and knife to be moved rearward or to initial position. The clutch mechanism and pedal connections may be of any ordinary known or suitable form, and it is not deemed necessary or desirable to further describe or show the same herein. My preferred form of pivoted safety plate-holder suitable for use in connection with and forming a part of my improved electrotype and stereotype shaving machine herein described and shown, and also adapted to be used with any ordinary and well known form of electrotype and stereo-

type shaving machine, is constructed as follows:

A horizontal rock-shaft 45 extends transversely above the plate-supporting bed, and 5 has its opposite ends journaled in upwardly and downwardly movable bearing blocks 46 which are slidably mounted between vertical guides or ways 47 on the end frames 8 at the opposite ends of the knife-supporting 10 head or carriage. Compressible springs 48 are interposed between the tops of these bearing blocks and adjacent retaining plates 49, so as to tend to press the bearing blocks downward and permit but yieldingly resist 15 any upward movement of the rock shaft 45 which is necessary or desirable in order to enable the device to operate efficiently when employed in the operation of shaving or planing plates of varying thickness. To 20 this rock shaft is fixed an angular lever arm 50 the main body portion of which is adapted to extend longitudinally of the bed and machine frame and horizontally over and parallel with respect to the top surface 25 of the bed and top surface of any electrotype or stereotype plate or other metallic plate to be operated upon, when the lever arm is in lowered horizontal position, as shown in full lines in Fig. 1. The lever arm 30 has a relatively short angular end portion 51 at its rear or pivoted extremity, adapted to extend downward from the rock shaft and in substantially perpendicular relation to the horizontal bed and main body portion 35 of the lever arm, when the arm is in lowered operative position. At the bottom of this perpendicular or depending angular portion 51 of the lever 50 is mounted a roller 52 which is rotatively supported by means of 40 an axle 53 which is mounted upon said lever in position to extend transversely with respect to and movable to raised and lowered positions with said lever. This roller is disposed transversely with respect to and 45 adapted to travel over the bed in advance of the knife and in contact with the top surface of any electrotype or stereotype plate or other metallic plate laid flat upon the bed, to be operated upon or shaved or planed. 50 The roller 52 is, by preference, thus rotatively supported upon the lever in a position slightly back of the axial center of the rock shaft 45, or axis of the lever 50, but beneath said rock-shaft and in advance of 55 the cutting edge of the knife, when the lever is in lowered or horizontal operative position.

A series of parallel plate-engaging transverse rollers 54 are rotatively supported 60 upon and in position to extend laterally on opposite sides of the main body of the lever 50 by means of a series of parallel axles or transverse roller-supporting rods 55 each of which is mounted upon, and, by preference, 65 in position to extend transversely with re-

spect to and on opposite sides of the main body of said lever, so that each axle or rod 55 is adapted to rotatively support a pair of rollers 54 located on opposite sides of the lever or roller-supporting arm 50. The 70 rollers are retained in rotative position upon the axles or rods 55 by means of retaining nuts 56 which are in threaded engagement with the outer ends of the rods and adapted to engage the adjacent outer ends of the 75 rollers upon said rods. The rods may be secured in fixed relation to the lever 50 by means of retaining screws 57 each of which engages a central portion of the rod to be held in place thereby. These transverse 80 rollers are thus supported in parallel relation to each other and all in the same plane with each other and in the same plane with the longitudinal center of the lever 50, but in such position that the bottom surfaces of 85 the rollers will all be in the same horizontal plane with each other but sufficiently below the level of the bottom of the lever 50, when the latter is in lowered horizontal position, so that the bottom faces of the rollers will 90 engage the top surface of any electrotype plate or stereotype plate or other metallic plate laid flat upon the bed, to be operated upon or shaved or planed.

In Fig. 3, is shown another ordinary and 95 well known form of electrotype and stereotype shaving machine, with parts broken away or omitted, only such parts being shown as are deemed necessary in order to enable the invention to be made, used and 100 understood by those skilled in the art. In the form of machine illustrated in Fig. 3, a knife-supporting head or carriage 58 is slidably mounted in position to extend 105 transversely across and over and to be moved back and forth lengthwise of a stationary plate-supporting bed 59, which is supported by a machine frame which may be of any desired ordinary and well known or suitable form. The knife-supporting 110 head or carriage 58 has a knife 60 mounted thereon in position to extend transversely with respect to the plate-supporting bed and transversely with respect to the direction of movement of said knife-supporting 115 head or carriage, the bottom edge of the blade being horizontal and adapted to engage and shave the top side of any electrotype or stereotype plate or other similar metallic plate 60' laid upon the bed in horizontal position, to be operated upon. The knife 60 is secured in operative position 120 upon the knife-supporting head or carriage, by means of a plate or knife-clamping jaw 61 and headed securing screws 62 which are in threaded engagement with the head, and adapted to hold the plate or clamping jaw 61 in securing engagement with the knife or blade.

The knife-supporting head or carriage 58 130

is operatively connected with a suitable source of power in the usual manner: A pair of horizontal toothed racks 62 are fixed to the carriage 58 in position to travel lengthwise of the plate-supporting bed on opposite sides of its longitudinal center. A main driving shaft 63 is rotatively supported in suitable bearings in the machine frame; and a counter-shaft 64, rotatively mounted in suitable bearings, is provided with spur pinions 65 fixed thereto and each in toothed engagement with a corresponding toothed rack 62. A spur gear wheel 66 is fixed to the shaft 64 and in toothed engagement with a spur pinion 67 fixed to the main driving shaft 63. A main driving wheel or belt pulley 68 is mounted in concentric relation to the main driving shaft, and adapted to be operatively connected with and disconnected from operative engagement with the main driving shaft by any desired ordinary and well known form of clutch mechanism suitable for the purpose. Such clutch mechanisms being in common use and well known in the art, it is not deemed necessary or desirable to describe the same herein.

In providing an electrotype and stereotype shaving machine of the kind shown in Fig. 3, with an improved safety plate-holder device or attachment constructed in accordance with my invention, I mount one or more angular bracket members 69 upon the traveling knife-supporting head or carriage 58. The bracket or bracket members comprise one or more upright angular arm portions 70 which are secured to the back of the knife-supporting head or carriage by means of suitable securing screws 71, or other ordinary suitable securing means; and horizontal bracket arms 72 extend forward from the upper extremity of the upright bracket portions 70 with which they are connected so as to form one integral piece, if desired. The forwardly extending bracket arms 72 are located at or near opposite ends of the knife-supporting head or carriage, with their forward ends in advance of the knife and in position to form suitable means for supporting the rock-shaft and rollers and pivoted lever mechanism of my improved plate-holder device or attachment in operative position upon the knife-supporting head or carriage.

The rock shaft 45 of my improved plate-holder attachment is adapted to be supported at its opposite ends by means of the forwardly extending bracket arms 72, so as to form a rocking or pivotal support for the roller-supporting arm 50 and the parallel rollers 52 and 54 which are mounted upon said roller-supporting arm or lever. The rock-shaft 45 may be provided at its opposite ends with suitable bearings which may be in the form of upwardly and downwardly

movable sliding bearing blocks 46 each slidably mounted in a socket or slot formed by a supporting member 73 secured to the end of the corresponding bracket arm 72; and compressible springs 48 may be interposed between the tops of these bearing blocks and the corresponding bracket arm 72, so as to tend to press the bearing blocks downward and permit but yieldingly resist any upward movement of the rock shaft 45 which may be necessary or desirable in order to enable the roller-supporting arm or lever to be raised and lowered as desired, and to operate in an efficient manner. The arm or lever member 50 is shown in lowered horizontal operative position in full lines in Fig. 3—and also in Fig. 1—and in raised position in broken lines in said figures.

From the foregoing description it is plain that my improved plate-holder device or attachment, including the rock shaft 45, the roller-supporting arm or lever member 50, with its depending angular portion 51, and the rollers 52 and 54 and their supporting axles or rods 55, all constructed and arranged as described in connection with Figs. 1 and 2 of the drawings, is adapted to be attached to the knife-supporting head or carriage of an electrotype or stereotype plate shaving machine of the form shown in Fig. 3, or any ordinary and well known form of stereotype or electrotype plate shaving machine, and the device so constructed is shown in Fig. 3, attached to an electrotype and stereotype shaving or planing machine of the simple form in which the knife is not adapted to be automatically raised and lowered, as it is in the form of machine shown in Figs. 1 and 2.

In operation the plate to be shaved or planed is placed in flat horizontal position upon the bed, by the operator. The roller-supporting arm or lever 50 is then lowered from the position in which it is indicated in broken lines in Fig. 3, to its lowered horizontal position as shown in full lines in Figs. 1 and 3. Pedal 43 is then pressed down so as to cause the knife-supporting head or carriage to travel in a forward direction over the plate to be shaved. When the knife-supporting head, with its knife in position to engage the plate to be operated upon, has reached its forward limit of movement, the pedal 44 is pressed so as to cause the driving mechanism to move the knife-supporting head or carriage in the opposite direction, with the parts in position for another cutting movement. During the cutting movement of the knife-supporting head or carriage, the operator holds or presses the lever or roller-supporting arm down so as to hold the rollers in engagement with the plate over which the rollers are caused to pass in advance of the knife. The plate is thus firmly and securely held down during the shaving or planing operation, and is pre-

vented from bending, buckling or cracking or from becoming distorted or in any way injured during the shaving or planing operation, regardless of the thickness or size of the plate to be operated upon. The plates, which, in practice are of varying thickness, are thus shaved and rendered of the desired uniform thickness with great facility and in such a manner that great speed of operation 10 is rendered possible without danger of buckling, breaking, distorting or injuring the plates operated upon.

A roller 74 journaled in suitable bearings 75 in supporting brackets 76 at the front 15 end of the machine, is adapted to engage the bottom face of the lever 50 and limit its downward movement when the lever has been carried forward with the knife-supporting carriage.

20 In the form of safety-plate holder device or attachment shown in Fig. 4, the rock-shaft 45,—which is adapted and intended to be mounted upon the carriage and supported in resilient journal bearings as 25 shown in Figs. 1 and 3,—is provided with an angular plate-holder arm member 77 having a depending angular end portion 78 fixed to and extending downward from said rock-shaft; and a plate-engaging member 30 in the form of a flat shoe 79 is fixed to the main body portion or plate-holder arm member 77 in position to slidably engage the top surface of a plate laid upon a plate-supporting bed, to be operated upon or 35 shaved in the manner already described. The plate 79 and plate-holder arm 77 are thus adapted to engage the top surface of a plate to be operated upon, and to travel over such plate in advance of the knife-supporting carriage during the cutting operation, in the manner in which the pivoted arm 50 with its rollers travel over and hold down a plate to be operated upon, as already 40 described. Anti-friction rollers 80 may be 45 rotatively mounted beneath and in parallel relation to and slightly back of the axial center of the rock-shaft 45, and adjacent to and back of the rear edge of the shoe member 79, in position to engage a plate to be 50 shaved or operated upon, said rollers being supported by means of an axle or rod 81 secured to the lower extremity of the depending angular plate-holder arm portion 78, and provided with retaining nuts 82 for retaining the rollers in operative position, as 55 shown in Fig. 4. These rollers are thus adapted to be yieldingly held in engagement with the plate to be operated upon, and to travel with the carriage and in advance of the knife.

I claim:—

1. In an electrotype and stereotype shaving machine, the combination of a plate-supporting bed, a knife-supporting carriage 65 extending transversely with respect to and

adapted to travel over the bed, a knife mounted on and movable with the carriage in position to engage and shave a plate supported upon the bed, a plate-holder member pivotally connected with the carriage and 70 extending forward in advance of the same and over the bed and acting to operatively engage and hold down a plate supported by the bed and engaged by the knife, and means for operating the knife-supporting 75 carriage.

2. In an electrotype and stereotype shaving machine, the combination of a plate-supporting bed, a knife-supporting carriage 80 extending transversely with respect to and adapted to travel over the bed, a knife mounted on and movable with the carriage over the bed and in position to engage a plate supported by the bed, a plate-holder arm pivotally connected with the carriage 85 and extending forward in advance of the carriage and over the bed, and a plate engaging member supported by said plate-holder arm and adapted to engage the top surface of a plate supported by the bed and 90 engaged by the knife, and means for operating the knife-supporting carriage.

3. In an electrotype and stereotype shaving machine, the combination of a plate-supporting bed, a knife-supporting carriage 95 extending transversely with respect to and adapted to travel over the bed, a knife mounted on and movable with the carriage over the bed and in position to engage a plate supported upon the bed, a transverse 100 rock-shaft located in front of the knife, resilient bearings upon the carriage and in supporting engagement with the rock-shaft, a plate-holder arm fixed to and movable with the rock-shaft and extending forward 105 in advance of the carriage and over the bed and adapted to operatively engage and hold down a plate supported by the bed and engaged by the knife, and means for operating the knife-supporting carriage. 110

4. In an electrotype and stereotype shaving machine, the combination of a plate-supporting bed, a knife-supporting carriage extending transversely with respect to and adapted to travel over the bed, a knife 115 mounted on and pivotally connected with the carriage and adapted to engage and shave a plate supported upon the bed, crank arm mechanism secured in fixed relation to and adapted to rock with the knife, a roller 120 located forward with respect to the knife and in position to raise and lower the crank arm mechanism and adapted to engage a plate supported by the bed and engaged by the knife, resilient bearings upon the carriage and in supporting engagement with the roller, a plate-holder member pivotally connected with the carriage and extending forward in advance of the carriage and over the bed and adapted to operatively engage 125 130

and hold down a plate supported by the bed, and means for operating the knife-supporting carriage.

5. In an electrotype and stereotype shaving machine, the combination of a plate-supporting bed, a knife-supporting carriage extending transversely with respect to and adapted to travel over the bed, a knife mounted on and pivotally connected with the carriage and adapted to engage and shave a plate supported upon the bed, crank-arm mechanism secured in fixed relation to and adapted to be rocked to raised and lowered position with the knife, a roller located forward with respect to the knife and in position to engage and raise and lower the crank arm mechanism and adapted to engage the top surface of a plate supported by the bed, resilient bearings upon the carriage and in supporting engagement with the roller, means for raising and lowering the roller, and means for reciprocating the carriage.

6. In an electrotype and stereotype shaving machine, the combination of a plate-supporting bed, a knife-supporting carriage extending transversely with respect to and adapted to travel over the bed, a knife mounted on and movable with the carriage in position to engage a plate supported upon the bed, a roller located forward with respect to the knife, resilient bearings on the carriage and in supporting engagement with the roller, and means for lowering and raising the roller into and out of engagement with the top surface of a plate supported by the bed, and means for reciprocating the carriage.

7. In an electrotype and stereotype shaving machine, the combination of a plate-supporting bed, a knife-supporting carriage extending transversely with respect to and adapted to travel over the bed, a knife mounted upon and movable with the carriage, for shaving a plate supported upon the bed, a roller-supporting arm attached to and movable with the carriage, and transverse roller mechanism rotatively supported upon said arm and movable with the arm and carriage in advance of the knife and in position to engage the top surface of a plate supported by the bed.

8. In an electrotype and stereotype shaving machine, the combination of a plate-supporting bed, a knife-supporting carriage extending transversely with respect to and adapted to travel over the plate-supporting bed, a knife mounted upon and movable with the carriage, for shaving plates to be supported upon the bed, a roller-supporting arm having articulate connection with the carriage and adapted to extend in front of the knife, transverse roller mechanism rotatively supported upon said arm and in front of the knife, and movable with the arm and

carriage over the plate-supporting bed and in advance of the knife in position to engage the top surface of a plate engaged by the knife and supported by the bed, and means for operating the carriage.

9. In an electrotype and stereotype shaving machine, the combination of a plate-supporting bed, a knife-supporting carriage extending transversely with respect to and adapted to travel over the plate-supporting bed, a knife mounted upon and movable with the carriage, for shaving plates mounted upon the bed, a roller-supporting arm pivotally connected with the carriage in position to extend in front of the knife, transverse axles mounted upon said pivoted arm, rollers rotatively mounted on said axles and in front of the knife and movable with the arm and carriage over the plate-supporting bed and in advance of the knife in position to engage the top surface of a plate supported by the bed, and means for operating the knife-supporting carriage.

10. In an electrotype and stereotype shaving machine, the combination of a plate-supporting bed, a knife-supporting carriage extending transversely with respect to and adapted to travel over the plate-supporting bed, a knife mounted upon and movable with the carriage, for shaving plates mounted upon the bed, a roller-supporting arm having articulate connection with the carriage and located in position to extend in front of the knife, transverse axles fixed to and extending laterally on opposite sides of said roller-supporting arm, rollers rotatively mounted on said axles on opposite sides of said roller-supporting arm and in position to extend in front of the knife and in engagement with the top surface of a plate supported by the bed, and means for operating the knife-supporting carriage.

11. In an electrotype and stereotype-shaving machine, the combination of a plate-supporting bed, a knife-supporting carriage extending transversely with respect to and adapted to travel over the plate-supporting bed, a knife mounted upon and movable with the carriage, for shaving plates to be supported by the bed, a transverse rock-shaft located in front of the knife, resilient journal bearings mounted upon the knife-supporting carriage and in supporting engagement with the rock shaft, a roller-supporting arm fixed to the rock shaft and extending forward from the same in front of the knife, transverse axles mounted upon and extending laterally on opposite sides of the roller-supporting arm, rollers rotatively mounted on said axles on opposite sides of said roller-supporting arm in position to extend in front of the knife and in engagement with the top surface of a plate supported by the bed, and means for operating the knife-supporting carriage.

12. In an electrotype and stereotype shaving machine, the combination of a plate-supporting bed, a knife-supporting carriage extending transversely with respect to and adapted to travel over the bed, a knife mounted upon and movable with the carriage, for shaving plates to be supported by the bed, a transverse rock-shaft located in front of the knife, resilient bearings upon the carriage and in supporting engagement with the rock shaft, a roller-supporting arm fixed to the rock shaft and extending downward and forward from the rock shaft and in front of the knife, a roller rotatively mounted upon said arm below and rearward with respect to the axial center of the rock shaft, transverse axles mounted upon and extending laterally on opposite sides of the roller-supporting arm and in front of said rock shaft, in position to engage the top surface of a plate to be supported by the bed, and means for operating the knife-supporting carriage.
13. In a plate-holder attachment for electrotype and stereotype shaving machines, a roller-supporting arm, a series of axles mounted upon and extending laterally on opposite sides of said arm, rollers rotatively mounted on said axles on opposite sides of and in perpendicular relation to said roller-supporting arm, the axes of said rollers being in parallel relation to each other and all in the same plane, a knife-supporting carriage, and means for connecting said roller-supporting arm in articulate relation to the knife-supporting carriage and in position to support said rollers in engagement with the top surface of a plate to be shaved.
14. In a plate-holder attachment for electrotype and stereotype shaving machines, a roller-supporting arm, a series of roller-supporting axles mounted upon and extending laterally on opposite sides of said arm, rollers rotatively mounted on said axles on opposite sides of the roller-supporting arm, the axes of said rollers being in parallel relation to each other and all in the same plane, a rock shaft fixed to one end of said roller-supporting arm and extending laterally on opposite sides of the same, a knife-supporting carriage, and means for pivotally connecting said rock shaft with the knife-supporting carriage and in position to support said arm and rollers in front of such carriage.
15. In a plate-holder attachment for electrotype and stereotype shaving machines, the combination of a roller-supporting arm, a series of roller-supporting axles fixed to and extending laterally on opposite sides of said arm, rollers rotatively mounted on said axles on opposite sides of the roller-supporting arm, the axes of said rollers being in parallel relation to each other and all in the same plane, a rock shaft fixed to one end of said roller-supporting arm and extending laterally on opposite sides of the same, a knife-supporting carriage, and resilient bearings upon the opposite ends of said rock shaft and adapted to be supported upon the knife-supporting carriage, for pivotally supporting such rock shaft upon such carriage.

Signed at Chicago, Illinois, July 18, 1918.
CHRISTIAN N. SMITH.
